(57) **CLAIM**

The ornamental design for a navigation device having a removable hard disk drive, as shown and described.

DESCRIPTION

FIG. 1 is a perspective view of a navigation device having a removable hard disk drive showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof with the supporter in the unfolded position; and,

FIG. 9 is a perspective view thereof with the hard disk drive in the removing condition.
